UNITED STATES PATENT OFFICE.

JOSEPH DAVIDSON, OF JERSEY CITY, NEW JERSEY, ASSIGNOR OF ONE-HALF TO
FREDERICK H. LUFT, OF PALISADE, NEW JERSEY.

AMUSEMENT DEVICE.

Application filed December 3, 1926. Serial No. 152,329.

The main object of this invention is to provide an amusement device suitable for resorts and beaches where such devices are provided for the amusement and merriment 5 of the people.

Another object of this invention is to provide an amusement device in the form of a plurality of passenger cars which are mounted on an endless moving cable, and swing 10 around an oval or similarly shaped track resulting in producing a number of sensations to the occupants of the passenger cars thereby creating much amusement and merriment to them.

Another object is to provide an amusement device in the form of a plurality of passenger carrying turn-tables which are coupled to an endless drum cable. The entire device is mounted on a track of oval or 20 other outline which is surrounded by an endless wall, which latter cooperates with the turn-tables for rotating the latter to produce one of a number of sensations to the users of the device.

Another object is to provide an amusement device which is capable of producing a number of sensations at the same time by providing a track which guides turn-tables on which passengers are seated first in a 30 straight line, then around a turn all the while that the turn-tables are spinning.

The above and other objects will become apparent in the description below in which characters of reference refer to like-named 35 parts in the drawing.

Referring briefly to the drawing, Figure 1 is a top plan view of the amusement device showing the turn-tables as mounted on the track.

Figure 2 is a sectional side elevational view of the device with a portion of the guide wall removed.

Figure 3 is a top plan view of one of the turn-table supports showing the rollers thereon for rotatably supporting the turn-tables of the device.

Figure 4 is an inverted plan view of Figure 3 showing the steering mechanism for maneuvering the turn-tables around the 50 turns of the track.

Figure 5 is an end elevational view of Figure 3 showing an elevational view of the steering mechanism.

Referring in detail to the drawing, the 55 numeral 10 indicates an oval track. This

track is a flat plane which is bounded around its entire outline by a guide wall 11. In the illustration the track is shown as oval, but the device may not be confined to this type of track as tracks having a fluted 60 or undulating outline may also be used to advantage. This track forms a passageway which is endless having two stretches which are alternated by curved stretches at the end of the straight stretches as is illustrated in 65 Figure 1. These curved stretches form semi-circular paths which are generated about studs 12 and 13. The studs extend upwardly from the track and serve as an axle, one axle for each, of the grooved pulleys 14 70 and 15. The pulleys have an endless cable 16 trained about them to which passenger carrying turn-tables are connected. The stud 13 on which the pulley 15 is mounted has a gear 17 secured thereto beneath the 75 track whose teeth are engaged by a worm 18 which extends from the shaft of a motor 19. This driving mechanism is located beneath the track of the device.

At spaced apart positions along the entire length of the cable pairs of arms are pivotally connected to the cable thru the use of yokes which are directly pivoted to the cable and which have one of their ends pivoted to the stated yokes 22, said arms 80 being indicated by the numerals 20 and 21. The yokes are used in pairs and are preferably spaced apart from each other as is illustrated in Figure 1. Each pair of levers 20 and 21 is coupled mutually together at 85 their opposite ends and are pivotally fixed to a bar 23 which extends to and is rigid with the turn-table carriages 24 from which the bars extend radially. These turn-table carriages 24 are mounted in front of the connected ends of the arms 21 and 22 so that 90 in being urged around the track the carriages are pushed. It is to be noted that the distance between the axis of the carriages 24 and the cable is greater than the distance 95 between the axes of the mutually pivoted ends of the arms 20 and 21 and the cable so that the tendency of the carriages is always to swing outwardly into contacting position with the inner surface of the guide 100 rail 11 which encircles the track.

The carriages are mounted on a pair of front wheels 25 and rear wheels 26. All of these wheels are journalled on axle members 27 which are pivoted to rigidly fixed axle 110

members 28. The swing axles 27 supporting the rear wheels 26 are provided with extending arms 29 which have connected thereto one of the ends of the levers 30 and 31 which 5 extend forwardly to the front wheels of the carriage. Said levers at their forward ends are connected to additional arms 32. A finger 33 extends forwardly from the swing axles 27 of the front wheels and these arms 10 are connected by a bar 34 which has a pin 35 extending downwardly therefrom from a position intermediate its length, which pin registers in a channel 36 having the same outline as the track of the device but is of 15 smaller dimension.

At right angled position on the carriages pins 38 are mounted in the same and span across recesses formed therein. In these recesses rollers 37 are supported on the pins 20 in such manner that the upper portions of the peripheries of said rollers project above the surface of the carriages. Each of the carriages supports a turn-table 39 which is provided with an axial hole at its center 25 which is slipped over the stud on the carriage. The turn-table is supported on the rollers and the rim is adapted to frictionally contact with the guide wall and be rotated thereby. The turntables are further provided with a plurality of frames which serve 30 as seats 40 for the carrying of the passengers. The turn-tables are rotatably mounted on the king bolts 41 which are mounted axially in members 24.

35 This device is adapted to serve the purpose of amusement and merriment by providing a plurality of sensations to the passengers. The latter seat themselves in the seats 40, all the seats being preferably filled 40 so that the turn-tables are perfectly balanced. The motor 19 is then started thereby actuating the worm and worm wheel, 18 and 17 respectively, which causes the grooved pulley 15 to be rotated. The cable 45 16 being trained about this pulley and the one at the opposite end of the track is moved longitudinally on the straight paths and around the outer halves of the pulleys 14 and 15. The arms 21 and 22 are so coupled 50 to the cable as to describe an arc outwardly when the carriages and turntables mounted on the carriages thru their weight exert a dragging force on the bars 23. As the momentum of the driving means increases the 55 drag of the turn-table and carriage of one unit causes the tendency of these members to lag behind and thereby the tendency if swinging outwardly is introduced to turn-table especially is this tendency aided and 60 abetted by the very construction and length of the arms 20 and 21 which are of shorter length than the distance between the axis

of the carriage and the cable of the device. The rim or periphery of the turn-table is in 65 constant contact with the wall of the track and is constantly being rotated while the device is in motion.

From the above it will be seen that an amusement device is presented which travels at a normal rate of speed on straight-away 70 paths, accelerating its speed on passing around turns all the while rotating the turn-tables, thus introducing a number of sensations to the passengers thereon.

To guide the carriages in a given path 75 the steering mechanism as illustrated in Figure 4, is provided on the carriages and the pins 35 by registering in the channel 36 of the track causes the wheels at the front and rear of the carriages to be rotated or 80 steered in the proper direction when passing around the curved portion of the track.

It is to be noted that certain changes in form and construction may be made without departing from the spirit and scope of 85 the invention.

I claim:

1. An amusement device comprising a track having straight paths alternated by 90 curved paths, a vertical wall bounding said track, said track having a grooved channel formed therein of the same shape as the outline of the track, wheeled carriages guided by said channel around said track, grooved pulleys mounted on said track, an 95 endless cable trained about said pulleys, and rotatable turn-tables mounted on said carriages, and means on said carriages registering in said channel for steering the former. 100

2. An amusement device comprising a track having straight paths alternated by curved portions, a guide wall encircling said track, said track having a channel therein midway the width of said track, spaced 105 apart pulleys mounted on said track, a cable trained around said pulleys, pairs of levers attached to said cable, the free ends of said levers being secured together, carriages positioned in front of said levers, a bar extending rearwardly from said carriages, and connected to the joined ends of said levers, turn-tables rotatably mounted on said carriages and having seats mounted thereon, swivelled wheels supporting said turn-table 110 carriages, a steering mechanism connecting said wheels, and means on said steering mechanism for cooperating with the channel of the track for swivelling said wheels when said carriages are passing around the turns 115 120 of the track. 120

In testimony whereof I affix my signature.

JOSEPH DAVIDSON.
